UNITED STATES PATENT OFFICE.

VINCENT BENDIX, OF CHICAGO, ILLINOIS.

ENGINE-STARTER.

1,354,157.

Specification of Letters Patent. Patented Sept. 28, 1920.

Application filed December 18, 1918. Serial No. 267,281.

To all whom it may concern:

Be it known that I, VINCENT BENDIX, a citizen of the United States, residing at Chicago, Cook county, Illinois, have invented 5 certain new and useful Improvements in Engine-Starters, of which the following is a specification.

My invention relates to a starter for an engine such as a gas engine and the like and 10 the object thereof is to provide a simple, efficient and reliable device of this character. My starter is of that type exemplified in 15 patents heretofore issued to me, for instance, Patent No. 1,116,370 dated November 10, 1914, and Patent No. 1,125,935 dated January 26, 1915, which starter is characterized 20 by a prime mover such as an electric motor and a transmission or drive for transmitting the power of the motor by means of 25 a rotatable shaft, such as a screw shaft, and a driving member such as a pinion mounted thereon, to a member of the engine to be started, such as the fly wheel thereof.

My present invention is concerned with 25 the transmission or drive of such an engine starter and consists in the provision of simple and efficient mechanism whose features of advantage and utility will be understood from the description hereinafter given.

30 In the drawings Figure 1 is an elevation partly in section of an engine starter embodying my invention; and Fig. 2 is a section on the line 2—2 of Fig. 1; and Figs. 3 and 4 views similar to Figs. 1 and 2 in respect to a modified form of construction.

Referring to the embodiment of my invention as herein shown, the starting motor which is an electric motor and is represented in part at A is here provided with an extended armature shaft 1 on whose outer end is screwed a stop nut 2 which by preference is more effectually held thereon by the cross pin 3.

To the inner end of this extended armature shaft which forms a driving shaft there is secured a driving head 4 by suitable means such as the key 5. This head is in the form of a disk of two diameters whereby there is formed on the outer side an annular 50 space for the purpose of receiving a coiled driving spring 6 of the clock spring type, the inner end of this spring being secured at 7 to the smaller diameter portion or hub of the driving head.

55 Upon the driving shaft 1 is mounted the screw shaft which is in the form of a hollow

shaft or sleeve 8 whose outer portion is provided with screw threads and whose inner portion has integral therewith a driven head extended in the form of an inclosing casing 60 for the driving head and the spring and acting as a means of attachment for the outer end of the spring. As shown, this driven head has an enlarged base portion 9 and a shell or inclosing portion 10 within which both the driving head and the driving spring are contained. The outer end of this spring is attached at 11 to the inner side of said shell portion. As a result this spring acts as a yielding driving connection between 65 the motor and its shaft and the screw shaft in order to accomplish the same general results set forth in my patents aforesaid.

Upon the screw threaded portion of the screw shaft there is screw threaded the driving member or pinion 12 provided with the weighted disk 13 and adapted to mesh with a rotatable part of the engine to be started such as the teeth 14^a of the fly wheel 14.

The parts are shown in Fig. 1 in their driving position, that is, the pinion is in mesh with the fly wheel and adapted to drive the fly wheel when the motor is operated. Describing a cycle of operation and starting with the pinion in its normal position as shown in dotted lines, this pinion is automatically advanced inwardly into mesh with the fly wheel as the result of the operation of the motor and consequent rotation of the screw shaft or sleeve 8. When the pinion has reached the limit of its inward movement and is in full mesh with the fly wheel as shown in full lines it will partake of the rotary motion of its screw shaft and will thereupon rotate the fly wheel and cause the engine to be started. When the engine has started on its own power the pinion will be automatically demeshed and returned to its normal or home position on the screw shaft.

The drive from the motor to the screw shaft is thus through the driving spring 6 and consequently the power is transmitted resiliently, and different conditions encountered in actual practice, particularly the condition known as going over compression points is fully taken care of by this driving spring and the pinion is therefore held in proper full mesh with the fly wheel during this time and prevented from vibrating. Moreover the spring absorbs the shock incident to the rather sudden change from

to, also for longitudinal movement thereof, a driving member on the sleeve, a drive spring between the two heads, and means for limiting such longitudinal movement of the sleeve on the shaft, said heads being nested one within the other.

8. In an engine starter, a drive or transmission comprising a driving shaft, a driving head secured thereto, a sleeve having a head at its inner end and mounted on the shaft for rotary movement therewith and with respect thereto, also for longitudinal movement thereof, a driving member on the sleeve, a drive spring between the two heads, and a stop nut on the outer end of the shaft for limiting the longitudinal movement of the sleeve thereon.

9. In an engine starter, a drive or transmission comprising a driving shaft, a driving head secured thereto, a sleeve mounted on the shaft for rotary movement therewith and also with respect thereto and having a driven head coöperating with the other head, said sleeve having a screw threaded portion, a spring coöperating with the two heads and forming a driving connection between them, a pinion screw

threaded on the sleeve for longitudinal movement thereof and rotary movement therewith, a stop nut on the outer end of the sleeve to retain the pinion thereon, and a stop nut on the outer end of the shaft to limit the longitudinal movement of the sleeve thereon.

10. In an engine starter a drive or transmission comprising a driving shaft, a driving head which is secured thereto and which is in the form of a disk of two diameters, thereby providing an annular space, a sleeve mounted on the shaft and having at one end a screw threaded portion and at its other end a driven head in the form of a sleeve or flanged disk inclosing the driving head, the sleeve and its head being mounted on the shaft for longitudinal movement and the flange of such head being extended to always cover the driving head or disk regardless of such movement, a spring of the clock-spring type located in said annular space and anchored to the two heads to form a driving connection between them, and a driving member mounted on said screw threaded portion of the sleeve.
